UNITED STATES PATENT OFFICE.

LOYD I. ALDRICH, OF PEORIA, ILLINOIS, ASSIGNOR TO HART OIL BURNER CO., OF PEORIA, ILLINOIS, A CORPORATION OF ILLINOIS.

SAFETY CONTROL MECHANISM FOR ELECTRICALLY-CONTROLLED FUEL-BURNING DEVICES.

Application filed September 18, 1923. Serial No. 663,576.

To all whom it may concern:

Be it known that LOYD I. ALDRICH, a citizen of the United States of America, residing at Peoria, in the county of Peoria 5 and State of Illinois, has invented certain new and useful Improvements in Safety Control Mechanism for Electrically-Controlled Fuel-Burning Devices, of which the following is a specification.

10 My invention relates to safety control mechanism for electrically controlled fuel burning devices.

The object of my invention is in the provision of the thermal safety control mechanism mounted in a combustion chamber, or 15 rather mounted in such position as to be affected by the combustion conditions in said chamber and co-operating with a conventional electrically operated fuel burning 20 device.

Another object of my invention is in the provision of a thermal safety control mechanism co-operating with a formal liquid fuel atomizing device in such manner as to control the operation thereof entirely from 25 combustion conditions.

A still further object of my invention is in the provision of a thermal safety control mechanism co-operating with an electrically 30 operated fuel burning device and the ignition means therefor, whereby either initial failure of ignition or lack of combustion conditions will result in the operation of said safety mechanism to break the circuit 35 to said fuel burning device.

Yet another object of my invention is in the special formation of my safety control member whereby an increased sensitiveness to temperature conditions results.

40 Other objects of my invention will appear in the following specification taken in connection with the annexed drawings, in which:—

Figure 1 is a side elevation partially in 45 section of my thermal safety control member.

Figure 2 is a detail showing of a fuel burning outfit and electric connections therefor illustrating the co-operation of my safety 50 control mechanism therewith.

My present safety control means for fuel burners is an improvement upon a similar control mechanism disclosed in my co-pending application, Serial Number 632,541, filed April 16th, 1923, entitled "Safety control mechanism for liquid fuel burners".

In Figure 2, I have illustrated my safety control mechanism in co-operative relation with my fuel burning device and control means therefor and in a co-pending application, Serial Number 647,444, filed June 25th, 1923, entitled "Liquid fuel atomizers", a complete description of said fuel burning device and control means is contained. In view of the fact that a full description of the fuel burner and its electric connection has been made in a co-pending application and as my present device includes mainly the safety control mechanism, per se, I have not thought it necessary to go to too great detail in the description of said fuel burning mechanism.

Briefly, my fuel burner mechanism includes an electric motor 10, as a power unit. A flexible connection 11 provides means for transmitting power to the burning device which includes an air pump 12, a rotary fuel pump 13 and a common tube 14, which carries the mixture of air and fuel under pressure through a discharge pipe 15, to the discharge nozzle 17 which is disposed within a formal combustion chamber, the combustion chamber in the drawings being shown but partially as at 16.

My fuel burning device has for its ignition means a gas pilot which is ignited by a spark mechanism, the whole ignition program taking place upon the initial movement of the burner and continuing but temporarily thereafter, there being means for controlling the time necessary for igniting the discharged fuel mixture. Generally the ignition means is shown at 17^a, adjacent the discharge nozzle within the combustion chamber. Inasmuch as my fuel burning device is electrically controlled there are included some main electrical portions that have become practically formal to electrically controlled fuel burner outfits. These members include a house thermostat 18 to

cated in any portion of the house or building where it is desired to maintain a uniform temperature.

The electrical circuits for the burning device include a high voltage circuit, usually 110 volts, coming in from the street, and a low voltage circuit, which includes the transformer 19. A relay switch 21 controls the supply of current from the transformer 19 to the electric motor 10 and the control circuits associated therewith. This relay switch, diagrammatically shown in Fig. 2, comprises a main switch bar 21 pivoted at 50 in such manner as to control the movement of the two-sub-switches 51 and 52 carrying contacts 55 and 70, respectively. The contact 55 engages a corresponding insulated terminal 56, and contact 70 engages a corresponding insulated terminal 71. When the free end 51 of the main switch arm is thrown upward by the lever 67, the sub-switches, due to the action of spring means (not shown) are thrown upward and close contact 55 on 56 and contact 70 on 71.

The movement of the main switch to open or closed position is controlled by the solenoids 21^b and 21^c disposed directly beneath the main switch adjacent its outer ends. These solenoids carry the plungers 48 and 49 so positioned that the upper ends thereof are adapted to engage the under sides of the opposite ends of the main switch. If the solenoid 21^b is energized, its plunger 49 moves the switch to closed position, and, upon de-energizing of the magnet, the plunger drops back, leaving the switch in closed position. If the other magnet 21^b is energized, its plunger 48 moves the switch to open position. The plunger 48 in this magnet is also operatively connected to a gas supply valve 54 by a link 53, which valve controls the supply of gas to the pilot light of the burner.

A safety switch mechanism 20 cooperates with the main switch mechanism in the following manner: The plunger 48 in the solenoid 21^b carries a bi-metallic strip 21^a which is adapted to close a circuit through the terminals 57 and 58 when the solenoid winding is heated by the energizing current flowing therethrough. The magnetic coil 20^a coacts with an armature 20^b provided with a hooked lower end as shown which is adapted to engage a pivoted latch member 20^c carrying an insulated contact 73 positioned to make contact with the terminal 72 when members 20^b and 20^c are in latched position.

In operating the safety switch, the expansion of the bi-metallic element on the plunger 48 of the solenoid 21^b, due to heating of the winding, closes a circuit through the leads 76 and 76^a and hence through the coil 20^a which attracts its armature 20^b, thus releasing the latch member 20^c and breaking the contact connection between the terminals 72 and 73, and thus opening the circuit of

the 110 volt lead 75 to the transformer 19, and motor 10.

The fuel supply valve for the burner is controlled by a diaphragm 61 actuated by the pressure from the blower 12. This diaphragm is mechanically connected to the relay switch mechanism through the longitudinal arm 62 at the inner end of which is a slip connection 63 with the arm 64 pivoted at 65 to the vertical lug 66. A substantially vertical lever 69 is pivoted to the outer end of the arm 64 and is reciprocable by movement of the diaphragm within the guideways 67 and 68. The purpose of the lever 69 is to raise the outer end 50^a of the main switch 21 whereby to actuate the sub-switches.

The structural features of my electrical control mechanism have been set out, and I will now describe the operation of the various switches and the circuits which they control. There are two leads 74 and 75 from the 110 volt supply line which are connected respectively to the relay or main switch 21 and the safety device 20 operated by the heating of the thermal element in the plunger 21^b. The 110 volt side of the transformer 19 is so connected to the line wires that both the main and safety switches in the 110 volt circuit must be closed in order that current may be supplied to the transformer and to the motor operating the fuel pumps.

The transformer 19 is also provided with a low voltage tap of 12 volts to which the leads 76 and 77 are connected. These leads supply the current to energize the solenoids 21^b and 21^c, and also the magnet 20^a.

The safety switch functions to automatically disconnect the 110 volt line if current flows through the solenoid 21^b sufficiently long to heat its winding and thereby cause the bimetallic strip in its plunger to close a circuit from the low voltage tap of the transformer through the safety magnet 20^a. This magnet when energized trips the pivoted lever 20^c, releasing the switch bar 20^b, and thereby opening the main line circuit. For purposes of brevity, solenoid 21^b will be designated the "on coil" and solenoid 21^c, the "off coil." In the "on coil" circuit, the current flows from the transformer to the usual house thermostat switch 18 located at any desired point, through said switch if closed to the "on coil," through its winding, and to a furnace thermostat 22, which, if closed, allows the current to return to the transformer. The house thermostat 18 and the furnace thermostat 22 must have their switches in closed position simultaneously in order that current may energize the "on coil" and operate the main switch. The plunger 48 of this coil, due to its upward movement, closes the main switch, opens the gas valve 54 through the linkage 53 to supply the pilot flame for ignition purposes and

maintains these parts in such position until the "on coil" becomes demagnetized when its circuit is opened by either the house thermostat or the furnace thermostat.

- 5 As previously explained, when the main switch is moved by coil 21^b to the "on" position, it carries with it a pair of movable contacts 70 and 55 on the sub-switches 51 and 52 which engage insulated terminals 56 and 71, respectively. The main switch is initially actuated by a current which is flowing through the house thermostat 18, but since it is not desirable to permit such current to flow therethrough for an appreciable length 10 of time, one of the sub-switches is arranged to short circuit the leads to said thermostat.

15 The "off coil" or solenoid 21^c is connected in a circuit which includes the low voltage tap of the transformer, the switch of the room thermostat 18, the insulated terminal 57 and the sub-switch 51. From an inspection of Fig. 2, it will be seen that this circuit can be broken either by the main switch being moved to its "off" position, or by the 20 opening of the house thermostat switch due to a lowering of the room temperature. The circuit breaking switch is closed only when the main switch is in its closed position. A rise in room temperature closes the contacts 25 of the thermostat 18 and causes a current to flow through the "off coil" 21^c, lifting the plunger 49 and tripping the main switch. This movement also opens sub-switch 52, de-energizes coil 21^b, and permits the plunger 30 35 48 to drop back to its initial position.

40 The above description of the main portions of my fuel burning device has been given mainly to show the co-operation of my present thermal safety control mechanism, and it may be seen that generally the house thermostat thru the relay switch controls the starting and stopping of the fuel burning device. However, in all fuel burning outfitts there must be some control mechanism and it is in the control mechanism for the above device that my present structure 45 has been developed.

50 The object of the safety mechanism is to prevent the operation of the fuel burning device and hence an unignited flow of fuel into the combustion chamber either when there is an initial failure of ignition or in the case of a failure of combustion conditions during the operation of the device.

55 My present thermal safety control mechanism is perhaps more properly named a "furnace thermostat" inasmuch as there is a temperature control means for making and breaking an electrical circuit.

60 Although in Figure 2, I have shown my present safety control member as projecting into a combustion chamber at a point near the discharge end of the fuel burning outfit, however, this is not the only place adapted 65 for its insertion and as a matter of fact, it is

usually located at a more convenient point, namely: in the smoke pipe of the ordinary furnace. My safety control member or furnace thermostat is composed of a housing portion 22^a which encases the contact portions to be later described. Screw threaded into a projecting portion 23 of the casing is a hollow metal tube 24 having a closed end 37. Loosely mounted in the brass tube is a cylinder or rod 25 of carbon or some other substance having a smaller co-efficient of expansion than the metal tube. Abutting the inner end of the non-expansible substance is a plunger 26 having an inwardly projecting stem 27, abutting the multiplying lever 28 fulcrumed at 29 within the housing 22. Abutting the opposite side of the multiplying lever, and at the opposite end thereof, is a rod 30 slidale in the bearings 31 and 32 within the housing and spring tensioned with relation to the multiplying lever by means of a coil spring 33 positively attached thereto by means of the pin 34, said spring being supported and encased within a screw threaded casing 35. A sleeve 36 frictionally engaging the shiftable rod 30 has a coil spring 38 fastened thereto as at 39. The upper end of said coil spring engages a yoke 40 pivoted on the knife edge as 41 to a portion 42 of the housing 22^a. The upper end of the pivoted yoke provides the contact portion 43 of the safety mechanism and said yoke is adapted to oscillate between the insulated contact point 44 and the projecting lug 45 within the casing. The 50 electrical connections to my safety control member are shown at 46 and 47 and it may be clearly seen that the movement of the yoke 40 is adapted either to make or break the electric circuit.

55 As stated before my safety control mechanism is adapted to operate either upon initial failure of ignition or later upon failure of combustion conditions and it may be clearly seen that it is the effect of combustion conditions upon the hollow metal tube 24 that effects the operation of the yoke 40 to make or break the electrical circuit. As stated before in the case of failure of ignition of the sprayed liquid fuel upon commencement of operation of the fuel burning device, the time switch located in connection with the relay switch and safety switch will remain in circuit due to making of contact between the yoke 40 and insulated contact point 44, and eventually throw out of circuit the electric motor providing power means for the device, unless said contact is broken in the safety control member. Under normal operation, with an immediate ignition of the discharged fuel mixture, temperature will be raised within the combustion chamber and said temperature will directly effect the metal tube 24 with the result that the consequent expansion thereof 60 65 70 75 80 85 90 95 100 105 110 115 120 125 130

will permit the carbon cylinder 25 contained therein to move outwardly due to the pressure of the spring 38. The multiplying lever 28 will be moved by the shiftable rod 37 to the right, said rod carrying with it the sleeve 36 thereon, the movement of which thru the action of the spring 38 forces the yoke to the right and thereby breaks the contact between the yoke and insulated point 44. It may be seen that the initial movement of the sleeve 36 carries the yoke with it thereby causing either a making or breaking of the contact, however, permitting further extension of the rod 37 in either direction.

With the breaking of the contact in my safety control member due to the sensitivity of the metal tube to the changes in temperature, the time switch briefly referred to, is thrown out of circuit and the fuel burning device is capable of continuous operation until checked either by the house thermostat or by a failure of combustion conditions that might subsequently effect my safety control member.

The above operation of my safety control member or furnace thermostat is thought clear, relative to the operation of the fuel burning device, in case of initial failure of ignition. However, relative to the failure of combustion conditions after initial ignition of the fuel mixture, I will say that under such conditions the consequent cooling of the brass tube results in a contraction thereof with the result that thru the series of plungers and levers the contact is made between the yoke 40 and the insulated contact point 44 thereby placing in circuit the time switch which after a determined period will throw out the safety switch connected therewith to break the electrical circuit including the electric motor and hence stop the operation of the device.

What I claim is:

1. A fuel burning device comprising means for projecting a fuel mixture into a zone of ignition, a combustion chamber, an electrical safety control mechanism for preventing the projection of the fuel mixture upon an initial failure of ignition or a failure of combustion conditions thereafter, said safety control mechanism comprising a switch including a movable contact member, a thermal member sensitive to combustion conditions for controlling the movement of said member, and a slip connection between the thermal member and the movable contact member for substantially immediately actuating the movable contact member upon initial movement of the thermal member in either direction.
2. A fuel burning device comprising means for projecting a fuel mixture into a zone of ignition, a combustion chamber, an electrical safety control mechanism for preventing the projection of the fuel mixture

upon initial failure of ignition, said safety control mechanism comprising a switch including a movable contact member, a member sensitive to combustion conditions for controlling the movement of said member, a slip connection between the member and the movable contact member for substantially immediately actuating the movable contact member upon initial movement of the member in either direction.

3. A fuel burning device comprising means for projecting a fuel mixture into a zone of ignition, a combustion chamber, an electrical safety control mechanism for preventing the projection of the fuel mixture upon an initial failure of ignition or a failure of combustion conditions thereafter, said safety control mechanism comprising a movable contact member, a member sensitive to combustion conditions for controlling the movement of said member, and a yielding connection between the member sensitive to combustion conditions and the movable member for substantially immediately actuating the movable member, upon initial movement of the member sensitive to combustion conditions, in either direction.

4. A fuel burning device comprising means for projecting a fuel mixture into a zone of ignition, a combustion chamber, an electrical safety control mechanism for preventing the projection of the fuel mixture upon an initial failure of ignition or a failure of combustion conditions thereafter, said safety control mechanism comprising separable contact controlling the electrical circuit, a movable member adapted to control the electrical circuit through said contacts, a thermal element sensitive to combustion conditions actuating said movable member, said parts being so arranged as to substantially immediately make or break the electrical circuit upon initial movement of the thermal member in either direction.

5. A fuel burning device comprising means for projecting a fuel mixture into a zone of ignition, a combustion chamber, an electrical safety control mechanism for preventing the projection of the fuel mixture upon an initial failure of ignition or a failure of combustion conditions thereafter, said safety control mechanism comprising separable contacts controlling the electrical circuit, a movable contact member adapted to control the electrical circuit through said contacts, a member sensitive to combustion conditions for actuating said movable member, said parts being so arranged as to substantially immediately make or break the electrical circuit upon initial movement of the member sensitive to combustion conditions in either direction.

6. A fuel burning device comprising means for projecting a fuel mixture into a zone of ignition, a combustion chamber, an

electrical safety control mechanism for preventing the projection of the fuel mixture upon initial failure of ignition or a failure of combustion conditions thereafter, said safety control mechanism comprising an electrical circuit, a switch in the same, and a thermostatic element responsive to the temperature of the combustion chamber

which opens the switch upon a rise in temperature and maintains it open during constant or increasing temperature, but closes said switch substantially at the commencement of any fall in temperature. 10

In testimony whereof I affix my signature.

LOYD I. ALDRICH.
